Primary Examiner — Barbara Fox(74) *Attorney, Agent, or Firm* — Sentinel IP; John Nielsen(57) **CLAIM**

The ornamental design for a tablet computer, as shown and described.

DESCRIPTION

FIG. 1 is a left side perspective view of a tablet computer showing the new design;
 FIG. 2 is a right side view thereof;
 FIG. 3 is a left side view thereof;
 FIG. 4 is a bottom view thereof;
 FIG. 5 is a top view thereof;
 FIG. 6 is a front view thereof; and,
 FIG. 7 is a rear view thereof.
 The broken lines show portions of the tablet computer that form no part of the claimed design.
